DISPLAY HOLDER FOR A WRITING INSTRUMENT OR THE LIKE

Richard L. Thurman, Beloit, Wis., assignor to The Parker Pen Company, Janesville, Wis., a corporation of Wisconsin

Filed Oct. 1, 1962, Ser. No. 71,947

Term of patent 14 years

(Cl. D58—12)

In the drawing:

FIGURE 1 is a top plan view of a display holder for a writing instrument or the like, showing my new design;

FIGURE 2 is a right-side elevational view thereof, the left side being substantially a mirror image thereof;

FIGURE 3 is a bottom plan view thereof;

FIGURE 4 is an end elevational view thereof taken from the bottom of FIGURE 1;

FIGURE 5 is an end elevational view thereof taken from the top of FIGURE 1;

FIGURE 6 is an enlarged fragmentary sectional view taken on line 6-6 of FIGURE 1;

FIGURE 7 is an enlarged fragmentary sectional view taken on line 7-7 of FIGURE 1; and

FIGURE 8 is an enlarged sectional view taken on line 8-8 of FIGURE 1.

The broken-line showing of a writing instrument in FIGS. 1, 2, 4, and 5 is for illustrative purposes only.

I claim:

The ornamental design for a display holder for a writing instrument or the like, as shown and described.
